UNITED STATES PATENT OFFICE.

MICHAEL J. HYLAND, OF ROCHESTER, NEW YORK.

BOTTLE-HOLDER.

1,342,747.

Specification of Letters Patent.

Patented June 8, 1920.

Application filed September 24, 1919. Serial No. 326,019.

To all whom it may concern:

Be it known that I, MICHAEL J. HYLAND, a citizen of the United States, and resident of Rochester, in the county of Monroe and State of New York, have invented certain new and useful Improvements in Bottle-Holders, of which the following is a specification.

The present invention relates to bottle holders and an object thereof is to provide a construction which is adapted to hold bottles of different sizes, the illustrated construction being designed for holding bottles containing an embalming fluid in order that the fluid may be drawn from the bottles through a tube and directed into the body.

To this and other ends, the invention consists of certain parts and combinations of parts, all of which will be hereinafter described, the novel features being pointed out in the appended claims.

In the drawings:

Figures 1 and 2 illustrate two side views of the holder with a bottle of one size held therein;

Fig. 3 is a side view of the holder fitted to a bottle of another size;

Fig. 4 is a section on the line 4—4, Fig. 3; and

Fig. 5 is a fragmentary view showing the connection between the main supporting band and one of the lateral supports.

Referring more particularly to the drawings 1 indicates the main supporting band which is preferably in the form of a wide strap of leather. To the opposite ends of this band, sustaining means is secured preferably in the form of straps 2 and 3, one of which carries a buckle 4 adapted to be engaged by the other strap to provide an adjustable sustaining means which is adapted to be passed around any suitable support such for instance as a nail 5. The supporting strap is adapted to support a bottle of any particular shape. In Figs. 1 and 2 the bottle 6 is long and narrow whereas, in Figs. 3 and 4 the bottle 7 is short and wide. In order to provide for the lateral support of the bottle, a band 8 is provided for co-operation with the bottle near its lower end. This band 8 is preferably secured to the supporting strap or band 1 by providing the band with two parallel slits 9 and passing the

lateral supporting band 8 through the two slits in the manner shown in Fig. 5. This 55 lateral supporting band is adjustable, being provided at one end with a buckle 10 to which the other end of the strap is adjustably secured. For supporting the upper end of the bottle a cord or the like is passed 60 through two openings 11 in the band 1 and through two openings 12 in the band 1 near the opposite end of the latter to provide two strands 13. These strands are twisted between the supporting band 1 to wrap about 65 the neck of the bottle in the manner shown.

It is apparent that the band 1 will adapt itself to bottles of any width and the two lateral supporting means are also adjustable to accommodate bottles of different widths. 70 The sustaining means is adjustable so that it may be fitted about any suitable support such as a nail, clothes hook, or any portion of furniture such as a bed frame, or chandelier. The holder firmly sustains the bottle 75 and at the same time permits the ready removal thereof.

What I claim as my invention and desire to secure by Letters Patent is:

1. A bottle holder comprising a supporting band, sustaining means connected to opposite ends of the band, an adjustable band at one side of the bottle and free from the band at the opposite side of the bottle for lateral support secured to the band, and a 80 second adjustable lateral supporting means for engaging the neck of the bottle, said second lateral supporting means embodying two flexible strands connected to the supporting band near both of its ends and 85 adapted to be twisted between the ends to pass about the neck of the bottle.

2. A bottle holder comprising a wide supporting band, sustaining means formed of two straps adjustably connected together, a 95 lateral supporting means for the lower end of the bottle formed of an adjustable strap passed through two slits in the supporting band, and a second lateral supporting means for engaging the neck of the bottle 100 embodying a cord passed through two openings in each end of the supporting strap to provide two strands adapted to be wrapped about the neck of the bottle.

MICHAEL J. HYLAND.
